UNITED STATES PATENT OFFICE.

JOSEPH BECKER, OF WASHINGTON, DISTRICT OF COLUMBIA.

COPYING OR ENLARGING CAMERA.

1,178,477.

Specification of Letters Patent.

Patented Apr. 4, 1916.

Application filed February 24, 1914. Serial No. 820,695.

To all whom it may concern:

Be it known that I, JOSEPH BECKER, a citizen of the United States, residing at Washington, in the District of Columbia, have invented a new and useful Improvement in Copying or Enlarging Cameras, of which the following is a specification.

The present patent application is identified for convenience of reference in my related applications or patents as Case A, and it makes specific reference to a number of such related applications or patents as follows: Case A, Serial No. 26,647, filed August 11, 1900; Case B, Serial No. 42,957, filed January 12, 1901; Case I, Serial No. 211,452, filed June 7, 1904; Case K, now Patent 1,103,342; Case L¹, now Patent 1,126,352; Case O, now Patent 1,103,343; Case T, now Patent 1,142,295; Case U, Serial No. 659,021, filed November 7, 1911; Case Y, Serial No. 732,488, filed November 20, 1912; British Patent 24,292 of 1911; British Patent 29,701 of 1912; and British Patent 5,317 of 1914.

25 The present invention relates to all classes of copying or enlarging cameras having any form or type of automatic focusing mechanism whatever; and it consists in means which shall, either directly or with very little modification, be applicable to such focusing mechanism of any type, to serve as 30 a constituent part of such mechanism, with the object of providing the three independent adjustments that I have discovered to be necessary to permit of setting and regulating any such mechanism for use with any one of different lenses.

If a given type of focusing mechanism (such as the linkage focuser of my said 40 Cases K and O or of my said British Patent 24,292/11, the radial cam focuser of my said British Patent 29,701/12, or of my said Case U and that of my said Case Y, or the eccentric focuser of my said Case T) is already provided with the three independent 45 adjustments that are needed to permit of using different lenses, the present invention is still partly useful in combination with such adjustable mechanism to increase the range of its adjustability; but the invention is primarily intended for use with focusing mechanism which does not contain within itself any direct means of adjustment; as, for instance, the cylindrical cam gear shown

in British patent to Thompson, No. 5,583 of 1903.

In the annexed drawings, which are made to scale in all essential particulars: Figure 1 is a longitudinal vertical section of a copying or enlarging camera with focusing mechanism normally constructed for use with a lens having a focal length f of 24 cm. and provided with three independently adjustable, but normally invariable, elements, to wit, m , m' , and the height of point A'', all of which have been properly regulated for the lens used which has a focal length phi (ϕ) of 28 cm with its nodal points N, N' situated and spaced as indicated in the figure. Fig. 2 is a similar vertical section, showing how the left end frame is properly located and fixed on its carriage by focusing on right infinity. Fig. 3 is another similar section, showing how the right hand end frame is properly located and fixed on its carriage by focusing on left infinity. Fig. 4, with a table of dimensions annexed, is the cancria of Fig. 1 as it might be used, without lever transmission, with any lens 13 of focal length f , equal 24 centimeters, for which the mechanism inclosed in casing X was specially designed. Fig. 5 shows the lens 14 used in Fig. 1 with a table of its various dimensions as they are after the lens has been mounted on the lens frame L.

The bed 10 of the camera is provided with two side brackets, such as 11, which are fixed to the bench by screws 12 and which extend upwardly to constitute the vertical side bars of the lens support or lens frame L. The lens 14, which is fully determined for all present purposes by plotting the positions occupied by its two principal foci F, F', and its two nodal points N, N', has in the present instance a focal length FN or N'F' or phi (ϕ) of twenty eight centimeters (28 cm.) and a relatively large internodal space NN' of six centimeters (6 cm.), the latter being selected relatively large for clearness.

The upper inside walls of the bench are grooved, as at 15, to form a horizontal slideway for two carriages 16, 16'. Carriage 16 itself is provided with a short horizontal slideway 17 for the foot 18 of the object frame O; and a clamp screw 19 permits of clamping such object frame O to and in any desired longitudinal adjustment on its said carriage 16. The corresponding slideway

17', foot 18' and clamp screw 19' at the right permit of clamping the image frame I to and in any desired longitudinal adjustment on its carriage 16'.

- 5 Carriage 16 has fastened to its under side by screws 20 a bracket 21 which supports a bearing 23 for a smoothly fitted pin 30, the common axis of pin and bearing being indicated by a dot A. Pin 30 is rigidly mounted 10 in a block 31 that travels in a horizontal slot 32 formed in the casing X which is fastened to bed 10 by screws 33, 34, 35. This casing X has a second horizontal slot 32' for a block 31', from which projects a pin 15 30' whose axis is indicated by a dot A'.

Blocks 31, 31' are connected by focusing mechanism of any type adapted for use with a camera having its lens frame stationary, and which is inclosed in casing X 20 to oblige such two blocks 31, 31' to move simultaneously and in the same direction, with a varying velocity ratio such as required for a lens of a definite but unknown focal length f .

- 25 Let a dot D indicate the so far unknown position into which the left hand axis A would be brought if this inclosed focusing mechanism could act, or be set, to carry the right hand block 31' with its axis A' to right infinity; and let a dot D' indicate the so far unknown position that the right hand axis A' would assume if the same inclosed focusing mechanism could act, or be set, to carry the left hand block 31 with its axis A to left infinity. These two dots D and D', when 35 properly located, constitute the inner terminals of the two co-varying constant product space elements AD and D'A' of the focusing mechanism. That is to say, if U, V, W, 40 Fig. 1, be three vertical marks on casing X indicating any three arbitrarily selected positions u , v , w of the object terminal A; and if U', V', W' be the three corresponding vertical position marks of the three positions u' , v' , w' of the image terminal A' 45 as determined and located by the mechanism

inclosed in casing X, then the horizontal distances of dots D and D' from these vertical marks will form constant products as follows:

$$uD.D'v' = f^2 \quad (1)$$

$$vD.D'v' = f^2 \quad (2)$$

$$wD.D'w' = f^2 \quad (3)$$

As long as the positions of D and D' are 55 unknown, the six factors uD and $D'v'$, vd and $D'v'$, wD and $D'w'$ must themselves remain unknown; but the four intervals uv , vw , and $u'v'$, $v'w'$, or their equivalents UV , VW , and $U'V'$, $V'W'$ are always directly 60 measurable on casing X. In the present instance

$$uv = UV = a = 32 \text{ centimeters}$$

$$vw = VW = b = 8 \quad "$$

$$u'v' = U'V' = a' = 24 \quad "$$

$$v'w' = V'W' = b' = 36 \quad "$$

If now the two unknown intervals VD , $D'V'$ be designated by

$$VD = y \text{ centimeters}$$

$$D'V' = y' \text{ "}$$

equations 1, 2, and 3 may be re-written in the following form:

$$(a+y)(y'-a') = f^2 \quad (4)$$

$$yy' = f^2 \quad (5)$$

$$(y-b)(y'+b') = f^2 \quad (6)$$

where the unknown quantities are three, to wit: y , y' and f .

These three equations are necessary and sufficient to determine the values of the three unknown quantities involved, and they yield:

$$y = (a' + b') \frac{ab}{ab' - a'b} \quad (7)$$

$$y' = (a + b) \frac{a'b'}{ab' - a'b} \quad (8)$$

By substituting the above measured values 90 of a , b , and a' , b' in these equations 7 and 8 we find:

$$DV = y = (24 \times 36) \frac{32 \times 8}{(32 \times 33) - (24 \times 8)} = 16 \text{ cm.}$$

$$D'V' = y' = (32 + 8) \frac{24 \times 36}{(32 + 36) - (24 \times 8)} = 36 \text{ cm.}$$

Therefore, by measuring off 16 centimeters from V to the right, we locate D, and by 95 measuring off 36 centimeters from V' to the left we locate D'.

In view of equation 5, we might, if desired, further derive

$$100 \quad f = \sqrt{yy'} = \sqrt{16 \times 36} = 24 \text{ cm.} \quad (9)$$

but the derivation of f is not necessary, except as serving to establish the principle that any focusing mechanism is fully determinable for all present purposes from three

arbitrarily selected positions of its terminal 105 connecting points.

Having located points D and D', their location should preferably be fixed in a permanent manner for use with any lens by boring holes 40, 40' in casing X of the exact 110 diameter required to provide a smooth but close fit for pins 30 and 30' which are to be inserted temporarily in such holes 40, 40', respectively, during the process of adjustment and regulation, as will be seen later on. 115

Carriage 16' has fixed to its under side

by screws 20' a bracket 50 which is provided with a straight slot 51. This slot 51 is preferably made inclined somewhat toward the right as shown; but it might be vertical or inclined at any other angle. A shouldered pin 52 that fits snugly in slot 51 may be slid along to any desired point of such slot and there be firmly clamped to the bracket 50 by nut 53 and washer 44. This pin 52, whose axis is indicated, in Fig. 1 only, by a dot A'', and pin 30', whose axis is A', are both engaged in the radial slot 54 of a slotted lever 55 which is pivoted by a pin 56 to a block 57. The block 57 is clamped 15 to the camera bed 10 by screws 58, 59, which also serve as guides for the walls of the horizontal slot 62 formed in block 57 to provide horizontally guided adjustment for pin 56, and for its axis indicated by point C.

20 The two slots 51, 54 are of the same width as seen in Figs. 1, 2, 3 to provide a smooth but close fit for the pins 52 and 30', which are made exactly of the same diameter.

The two end frames O and I are preferably made open with removable screens 66 and 66' so that either frame may be focused on infinity, through the other, without removing the other frame by simply removing the screen 66' or 66 contained in such other

30 frame.

The central point of the object plane 66 is at P, and the central point of the image plane 66' is at P' and any focusing mechanism that is operative must keep these two points respectively coincident with two conjugate foci of the lens in conformity with Newton's formula, to wit:

$$PF \cdot F'P' = \varphi^2 \quad (10)$$

40 where phi (φ) is the generally unknown focal length FN or N'F' of the lens to be used. This result is insured by means of three independent adjustments, to wit: 1, adjustment of the object frame connection 45 on carriage 16 at the left; 2, adjustment of the image frame connection on carriage 16' at the right; 3, adjustment of the constant velocity ratio CA''/CA' in lever 55.

1. *Adjustment of the object frame connection.*—Pin 30 is withdrawn to free the object carriage 16 which is then slid up into its zero position, the position of Fig. 2, where axis A has been brought into coincidence with axis D and distance AD is 55 nil. To insure this coincidence and to temporarily lock carriage 16 exactly in this its zero position, pin 30 is reinserted in bearing 23 so as to project as a slide bolt from bearing 23 into bore 40. While carriage 16 is thus held in its zero position, the image screen 66' is removed, the clamp screw 19 is loosened and the object frame O, now free, is sharply focused on infinity or parallel rays from the right, and then it is locked to 60 its carriage 16 by tightening screw 19.

Point P is now coincident with F, as seen in Fig. 2, and A is coincident with D; that is to say, distances PF and AD are both *nil*. Pintle 30 is now withdrawn from bore 40 and carriage 16 is slipped back to be reconnected with block 31 of the mechanism, as shown in Fig. 1.

The terminal point A, Fig. 1, may henceforth be considered as fixed with relation to the object plane P at an invariable distance 75 of 19 centimeters represented by the length of the imaginary horizontal connecting bar m . The terminal D may similarly be considered as held in fixed relation to the stationary focal plane F of the lens at an invariable distance of 19 centimeters represented by the length of a similar imaginary connecting bar x , Fig. 1; and the adjustment, therefore, has simply served to make these two imaginary connecting bars m and x exactly equal to each other. The adjustment also results in making the inclined line, that would join points P and A of the object frame in Fig. 2 coincident and identical with the inclined line that would join the fixed points F and D of the lens frame; so that, after adjustment as in Fig. 1, where the two lines PA and FD are separated, they remain equal and parallel, determining a parallelogram PFAD, with its horizontal 95 sides PF and AD variable, but constantly equal to each other; PF being the left variable Newtonian space element of the lens, and AD being the left variable Newtonian space element of the mechanism.

2. *Adjustment of the image frame connection.*—Pin 52 is shifted to any high position in slot 51, such as that seen in Fig. 2, and it is temporarily clamped to bracket 50 in such position by lightly tightening 105 nut 53. Pin 30' is now removed from block 31' to free carriage 16', which is then shoved along on bed 10, causing lever 55 to turn on C as fulcrum. This motion of carriage 16' is continued until the slot 54 of lever 55 110 has been brought into exact register with bore 40' at D', as indicated in Fig. 2; and such registration is insured and maintained by inserting pin 30' through slot 54, as lock bolt, into bore 40'. The lower end C of lever 55 should now be freed by loosening screws 58, 59; and pin 30', Fig. 2, is thus prepared to act as a stationary fulcrum for lever 55, while carriage 16' is slid to the right, causing block 57 and point C to shift 115 to the right. This shifting is continued until the bracket slot 51, and the lever slot 54, have been brought into perfect register as in Fig. 3, and the registration of the two slots is insured by inserting a locking block 120 63. Thereupon block 57 is firmly clamped to bed 10 by tightening screws 58 and 59. Carriage 16' and lever 55 are now held in what constitutes their zero position not only 125 for the present lens 14, but for all sizes and 130

forms and types of lenses. The fulcrum block 57 may, therefore, be more firmly fixed to bed 10 in its thus determined permanent location by inserting a screw or other permanent fastener 61 that fits nicely through a hole 60 of block 57 and is driven into the wooden base. While carriage 16' is thus held in its zero position, Fig. 3, the object screen 66 is removed, the image screen 66' 10 is inserted, and, having loosened clamp screw 19', the image frame I is set sharply in focus on parallel rays from the left, and then the screw 19' is retightened to lock the image frame I in its thus automatically determined proper relation to its carriage 16'.

The equality of the still undetermined imaginary bars m' and x' is thus established for any height that may later be found for the path $D''A''$ by means of the third adjustment.

In order to set the carriage 16' free for such third adjustment, pin 30' is now withdrawn from bore 40', and block 63 is withdrawn from slots 51, 52.

25 *3. Adjustment of the constant velocity ratio CA''/CA' .*—The only thing that remains to be done is to determine the proper value of the velocity ratio CA''/CA' . This ratio CA''/CA' is varied at will by changing the level of the horizontal path described by pin 52; that is to say, by shifting the said pin 52 from the high position of Fig. 3, which was arbitrarily selected in order to make adjustment 2, down to the proper elevation which it must occupy in order to secure the displacements that are required by the particular lens 14 which is being used.

Immediately after completion of adjustments 1 and 2, pin 30' and block 63, seen in Fig. 3, were removed, so that pin 52 now constitutes the only remaining connection between the carriage 16' and lever 55, and the image frame I can be slid along freely on bed 10. The object frame O, however, having been connected with block 31 as the result of adjustment 1 is not free, but it may be brought into any desired position on bed 10, that of Fig. 1, for instance, by actuating the focusing mechanism inclosed in casing X; and this operation simultaneously brings the terminals A and A' into the positions V and V' shown in Fig. 1. The object frame O is then temporarily clamped to bed 10 in such selected position of Fig. 1 and a test object is mounted in its temporarily held object plane P. The image plane P' is now sharply focused, on the object plane P by sliding the carriage 16' along on bed 10, and when the sharpest focus has been found the image frame I is temporarily clamped to bed 10 in its thus determined conjugate position. Pin 52 is now loosened and slid down in slot 51, until the lever 55, turning on C has been brought into the position of

Fig. 1 where its slot 54 registers exactly with the bore in block 31'. Pin 30' is then inserted through slot 54 and remounted in its block 31', and then pin 52 is firmly clamped to its bracket 50 by tightening nut 73 53. The temporary clamps used to hold carriages 16 and 16' in position on bed 10 are now removed and the device is fully adjusted as shown in Fig. 1 and ready for use. Pin A'', Fig. 1, will now travel along the horizontal line A'' D'' and at such rate as to pass successively through the three points u'', v'', w'' as pin A' passes successively through the three points u', v', w' . The zero position of A'' is D'' just as the zero position of A' is D' and the ratio $D''A''/D'A'$ of corresponding displacements is equal to the constant ratio CA''/CA' of the two variable lever arms CA'' and CA'. This ratio is most conveniently measured on the vertical through C, Fig. 1, where the two lever arms CA'' and CA' are shortest, being found equal to 98 and 72 centimeters, respectively; and we, therefore, have:

$$\frac{D''A''}{D'A'} = \frac{CA''}{CA'} = \frac{98}{72} = \frac{49}{36} \quad (11)$$

It was established above, by means of equations 1 to 9, that the original focusing mechanism contained in casing X determines constant product space elements AD and D'A' in accordance with the formula

$$AD \cdot D'A' = f^2 = 24 \times 24 \quad (12)$$

but the focusing mechanism required for lens 14 must act to produce constant product space elements AD and D''A'' in accordance with the formula

$$AD \cdot D''A'' = \varphi^2 = 28 \times 28 \quad (13)$$

Dividing equation 13, term for term, by equation 12 and noting that the space element AD is identical in the two equations, we finally obtain

$$\frac{D''A''}{D'A'} = \frac{\varphi^2}{f^2} = \frac{28 \times 28}{24 \times 24} = \frac{49}{36}$$

which is in exact accordance with equation 11, as it should be, that is to say, omitting numerical values, we have the general algebraic equation

$$\frac{D''A''}{D'A'} = \frac{CA''}{CA'} = \frac{\varphi \cdot \varphi}{f \cdot f} \quad (14)$$

To facilitate numerical verification of the principles involved, all except one of the dimensions shown in Fig. 1 have been selected so as to be expressible in whole numbers as follows: The three selected values of the object frame space element AD are

$$uD = 48 \text{ cm}$$

$$vD = 16 \text{ cm}$$

$$wD = 8 \text{ cm}$$

The three corresponding and mechani-

cally determined image frame space elements D'A' are

$$\begin{aligned} D'w' &= 12 \text{ cm} \\ D'v' &= 36 \text{ cm} \\ D'w' &= 72 \text{ cm} \end{aligned}$$

5

and the three derived image frame space elements D''A'' are

$$\begin{aligned} D''u'' &= 16\frac{1}{3} \text{ cm} \\ D''v'' &= 49 \text{ cm} \\ D''w'' &= 98 \text{ cm} \end{aligned}$$

10

The longitudinally adjustable connections are

$$\begin{aligned} m &= x = 19 \text{ cm} \\ m' &= x' = 25 \text{ cm} \end{aligned}$$

15

The horizontal distance Dd' between the original zero points D, D' is

$$Dd' = 26 \text{ cm}$$

and the horizontal distance Dd'' between the final zero points D, D'' is

$$Dd'' = 18 \text{ cm}$$

20

and, in accordance with equation 5 of my said British Patent 29701/12, we must, and do, have

$$m + Dd'' + m' = FN + NN' + N'F' = FF' \quad 30 \text{ or}$$

$$19 + 18 + 25 = 28 + 6 + 28 = 62$$

25

To permit of using the focusing mechanism inclosed in casing X and originally made for a lens of focal length f equal 24 cm, in combination with a lens of focal length (φ) equal to or smaller than 24 cm, the pin 52 must have free adjustment through the position where the distance CA'' is exactly equal to CA' without being interfered with by pin 30'. For this reason the lever 55 is made extra thick and the pins 30' and 52 are made so as to project into slot 54, from opposite sides, less than half way through the thickness of the lever.

35

Slot 51 in bracket 50 can be made sufficiently long to extend below the horizontal path of axis C so that axis C may be brought into its proper permanent position by simply bringing it into register with the middle of such extended slot, and this either with or without the aid of the auxiliary lock block 63, as may be preferred.

40

50

55

General remarks.

60

NOTE 1.—The original focusing mechanism in casing X, with terminals A, A' real and the two inner terminals D, D' absent, was of the type represented by case 7, page 12, of my said British Patent 29701/12.

NOTE 2.—By structurally adding the two inner terminals D, D' it became of the type represented by the complete form shown in Fig. 15 of the same patent.

65

NOTE 3.—In the final focusing gear com-

prising the lever 55 to determine co-varying Newtonian space elements AD and D''A'', Fig. 1, the inner terminal D'' is purely imaginary and the mechanism is of the type represented by case 3, page 12, of the same 70 said British Patent 29701/12.

NOTE 4.—Any focusing mechanism represented by one of the twelve cases noted on page 12 of my said British Patent 29701/12 can first be converted into my complete 75 form, Fig. 15 of the same patent, by structurally adding the omitted Newtonian terminal or terminals as was done above for the focusing mechanism in casing X, and then the principles herein disclosed can be 80 applied without difficulty.

NOTE 5.—The general three-point adjustment for three different finite values of the copying factor n as illustrated in Fig. 16 of my said British Patent 29701/12 is applicable in the present case, being particularly valuable here, as in both of my said prior British Patents 24292/11 and 29701/12 wherever the lens used is specially designed for the actinic region of the spectrum, or 90 else specially designed for values of the copying factor n ranging between given finite limits.

NOTE 6.—The present invention may be considered as a development of the principles first enunciated in Notes 5 and 6, page 20, of my prior U. S. application, Case Y, Serial No. 732,488, filed November 20, 1912.

NOTE 7.—The principles involved are most easily explained when the lens is stationary, as in the form selected for illustration; but either end frame O or I might be the stationary frame instead, and in certain forms it might be advantageous to have all three frames O, L, I freely movable on the 100 slideway 10, with casing X directly connected to and moving with the lens frame.

NOTE 8.—Inevitable errors in grinding and mounting, and, principally, unavoidable variations in the refractive index of different casts of the same optical glass, make it extremely difficult to produce two objectives exactly alike in all particulars; and therefore, all lenses must, for present purposes, be treated as different lenses. Hence, 115 even in constructing a camera for use with a given type and size of lens, as in Fig. 4, it is preferable to use an adjustable form of my invention, because the adjustments permit of making proper allowance for all accidental departures, and of surely securing in all cases the highest attainable performance of the particular lens used.

NOTE 9.—No special form of focusing mechanism is illustrated herein because the 125 invention is capable of use with any form; and casing X is, therefore, supposed to contain any preferred focusing mechanism which might have its terminals A and A' connected directly with the two end frame 130

carriages, as in Fig. 4, to move the points P and P' through the conjugate position determined, for any lens of focal length f equal to 24 centimeters, by either one and hence both of the lens formulæ given as equations 1 and 2 of my said Case L¹ or of my said British Patent 5317/14.

NOTE 10.—The principle that focusing gear having a constant velocity ratio transmission, with adjustments for changing the velocity ratio as required to adapt the gear for use in combination with any one of different lenses, must change such velocity ratio in proportion to the square of the focal length of the lens, was established as a general principle for "optical focusers" in a paper dated January 23, 1905, of my said Case B, and this "focus-squared principle" is involved in my so far described focusers, as follows: *first*, with continuously adjustable velocity ratio in the approximately accurate optical focusers, Figs. 33 and 57^b of my said Case A; *secondly*, with 3 value adjustable velocity ratio in the approximately accurate optical focuser, Fig. 10 of my said Case B, where the 3 values of the focal length are as 3, 4, and 5, while the corresponding 3 values of the velocity ratio are as 9, 16, and 25; *thirdly*, with fixed velocity ratio in the theoretically accurate optical focuser, Fig. 2, of my said Case I; *fourthly*, with continuously adjustable velocity ratio in the theoretically exact mechanical focuser of the present application, Case Ab. As this fourth and herein made disclosure shows my first complete and theoretically exact solution of the mechanical problem involved in the said "focus-squared principle" I am making all claims thereon in the present application, Case Ab.

NOTE 11.—Figs. 33 and 57^b of my said Case A and Fig. 10 of my said Case B disclose "optical focusers" having an approximately constant velocity ratio transmission with adjustments for changing the value of such velocity ratio as required by any one of different camera lenses and in such manner as to be substantially independent of another adjustment so as to permit of easily securing exact two-point correspondence between the focuser and the camera lens; but the present application, Case Ab, contains the first disclosure of a focuser having an "accurately constant velocity ratio transmission" with adjustments for changing the value of such accurately constant velocity ratio in strict proportion to the square of the focal length of the camera lens in accordance with the principle of Note 10, above, and, moreover, in such manner as to be absolutely independent of two other independent adjustments so as to permit of securing exact 3-point and even 3-and-all point correspondence of the focuser with any one of different lenses.

NOTE 12.—I am aware that Cook, in Fig. 3 of his British Patent No. 12,734 of 1904 shows a slotted lever g which might easily be confounded with my constant velocity ratio lever 55; but such Cook lever g moves its pintles b' and f' along paths that are perpendicular instead of parallel, and it really constitutes the varying velocity ratio focusing mechanism proper.

NOTE 13.—In accordance with a convention adopted in Figs. 12 to 15 of my said Case T, the imaginary bars x and x' of Fig. 4, being both invariable, after the lens 13 has been mounted, are shown black; whereas the imaginary bars m and m' , being adjustable, are left white; and in Fig. 1, according to the same convention, the imaginary bar x , being alone invariable, is alone shown black.

NOTE 14.—The horizontal adjustment of fulcrum C, once made for a given lens, is final for all lenses. It is, therefore, an "auxiliary adjustment" which should not be confounded with any one of the "3 main adjustments" that are at all times necessary, as at 19, 19', and 52, to secure 3-point correspondence of the focuser with any one of different lenses; whereas such "auxiliary adjustment" serves merely to insure that the last two of the said 3 main adjustments shall be absolutely independent; and I have found that a similar "auxiliary adjustment" is useful in focusers having only "2 main adjustments," as in the approximately accurate optical focusers, shown in Fig. 33 of my said Case A and Fig. 10 of my said case B.

NOTE 15.—The velocity ratio phi square on f square (ϕ^2/f^2) of terminals A'' and A', being constant by equation 14, is evidently equal to the ratio of any simultaneous finite displacements of such terminals, and any mechanism that is capable of producing simultaneous displacements of A'' and A' in such constant ratio must be considered as an equivalent of my lever transmission CA'A''. See Robert Willis, *Principles of Mechanism*, London, 1870, pages 12 and 13, article 20. The velocity ratio of terminals A and A', on the other hand, is necessarily a "varying velocity ratio" whose value changes with every change in position and can only be determined as the ratio of infinitely small simultaneous displacements.

NOTE 16.—Any focusing agent may according to the rules of the English language be termed a focuser. In my specifications, however, the term "focuser" has a restricted meaning which is most easily specified by the citation of existing patents. Thus "optical focusers," in the sense in which I use the term, are seen for instance in the focusing means of the following patents, to wit: Nicour, 71,205 of 1867; 130

Bragg, 339,736 of 1886; Berthon, 419,910 of 1890; Cogswell, 484,179 of 1892, and German Patent 188,342 of 1907 to du Bois-Raymond; whereas "mechanical focusers", 5 in the sense in which I use the term, are seen for instance in the focusing means of the following patents, to wit: German Patent 102,004 of 1897 to Carpentier, my said Case K, now Patent 1,103,342, and my 10 said Case T now Patent 1,142,295.

I claim:

1. In a copying or enlarging camera comprising a support for the object plane, a support for the lens and a support for 15 the image receiving plane, and ways for guiding two of such supports with relation to the third in order to vary their relative distances as required to produce images of various desired sizes, of focusing mechanism 20 for mechanically connecting such three supports to keep the said end of image planes mutually in focus on each other throughout all displacements of the supports, such mechanism comprising a constant 25 velocity ratio mechanism with adjustments to vary the velocity ratio as required for different lenses.

2. In a copying or enlarging camera comprising a support for the object plane, a support for the lens and a support for the 30 image receiving plane, and ways for guiding two of such supports with relation to the third in order to vary their relative distances as required to produce images of various 35 desired sizes, of focusing mechanism for mechanically connecting such three supports to keep the said end of image planes mutually in focus on each other throughout all displacements of the supports, such 40 mechanism comprising a constant velocity ratio mechanism with adjustments to vary the velocity ratio as required for different lenses; also 45 adjustments in two of the three normally rigid connections that must be established between such mechanism and the said three supports respectively.

3. In a copying or enlarging camera comprising a support for the object plane, a support for the lens and a support for the 50 image receiving plane, and ways for guiding two of such supports with relation to the third in order to vary their relative distances as required to produce images of various desired sizes, of focusing mechanism 55 for mechanically connecting such three supports to keep the said end of image planes mutually in focus on each other throughout all displacements of the supports, such mechanism comprising a constant velocity 60 ratio mechanism with adjustments to vary the velocity ratio as required for different lenses; also adjustments in two of the three normally rigid connections that must be established between such mechanism and the 65 said three supports respectively; and means

to permit of reducing the Newtonian space elements of such mechanism to zero value, for the purpose set forth.

4. The combination with a photographic camera comprising a support for a lens, a support for an image plane, and guides to 70 permit of changing the relative position of said two supports as required to set the camera in focus on an object; of a focuser for determining the said "in-focus relative 75 position" of the said supports corresponding to any given distance of the said object; such focuser comprising relatively movable elements whose relative position is determinable as dependent upon the distance of 80 the said object from the said lens support, also mechanism connecting the said relatively movable focuser elements with the said lens support and the said image plane support; such mechanism itself comprising 85 a constant velocity ratio transmission; such transmission having adjustments for changing the value of its said constant velocity ratio in proportion to the square of the focal length of the particular lens that is to be 90 used in the combination.

5. The combination with a photographic camera comprising a support for a lens, a support for an image plane, and guides to 95 permit of changing the relative position of said two supports as required to set the camera in focus on an object; of a focuser for determining the said "in-focus relative position" of the said supports corresponding to any given distance of the 100 said object; such focuser comprising relatively movable elements whose relative position is determinable as dependent upon the distance of the said object from the said lens support, also mechanism connecting the 105 said relatively movable focuser elements with the said lens support and the said image plane support; such mechanism itself comprising a constant velocity ratio transmission; such transmission having adjustments 110 for changing the value of its said constant velocity ratio in proportion to the square of the focal length of the particular lens that is to be used in the combination; such constant velocity ratio transmission 115 comprising a lever and another part with a pivot pivotally connecting such lever and other part, such pivot being adjustable along said lever and on the said other part in such manner that the two paths of adjustment shall be parallel when the said lever and the said other part occupy the relative position they should occupy when the said object plane is at infinity.

6. The combination with a photographic 125 camera comprising a support for a lens, a support for an image plane, and guides to permit of changing the relative position of said two supports as required to set the camera in focus on an object; of a focuser 130

- for determining the said "in-focus relative position" of the said supports corresponding to any given distance of the said object; such focuser comprising relatively 5 movable elements whose relative position is determinable as dependent upon the distance of the said object from the said lens support, also mechanism connecting the said relatively movable focuser elements with 10 the said lens support and the said image plane support; such mechanism itself comprising a constant velocity ratio transmission; such transmission having adjustments for changing the value of its said constant 15 velocity ratio in proportion to the square of the focal length of the particular lens that is to be used in the combination; such constant velocity ratio transmission comprising a lever and a pivot pivotally connecting said 20 lever with the said image plane support; such pivot being adjustable along said lever and on the said image plane support in such manner that the two paths of adjustment shall be parallel when the said lever and image plane support occupy the relative position that they should occupy when the said object plane is at infinity. .
7. The combination with a photographic camera comprising a support for a lens, a 30 support for an image plane, and guides to permit of changing the relative position of said two supports as required to set the camera in focus on an object; of a focuser for determining the said "in-focus relative 35 position" of the said supports corresponding to any given distance of the said object; such focuser comprising relatively movable elements whose relative position is determinable as dependent upon the distance of the said object from the said lens support, also mechanism connecting the said rela-

tively movable focuser elements with the said lens support and the said image plane support; such combination having main adjustments to permit of securing exact correspondence of the said focuser with any one of different lenses for at least 2 differently distant positions of the said object; and an auxiliary adjustment, such as that of fulcrum C, to permit of making two 50 of such main adjustments absolutely independent. 45

8. The combination with a photographic camera comprising a support for a lens, a support for an image plane, and guides 55 to permit of changing the relative position of said two supports as required to set the camera in focus on an object; of a focuser for determining the said "in-focus relative position" of the said supports corresponding to any given position of the said object; such focuser comprising relatively movable elements whose relative position is determinable as dependent upon the position of the said object, also mechanism 60 connecting the said relatively movable focuser elements with the said lens support and the said image plane support; such mechanism itself comprising a substantially constant velocity ratio transmission; such 70 transmission having adjustments for changing the value of its constant velocity ratio substantially in proportion to the square of the focal length of the particular lens that is to be used in the combination. 75

In testimony whereof, I have signed my name to this specification in the presence of two subscribing witnesses.

JOSEPH BECKER.
